DESIGN FOR A VELOCIPEDe FRAME MEMBER

Samuel A. Snell, Toledo, Ohio, assignor to The American-National Company, Toledo, Ohio, a corporation of Ohio

Application March 3, 1938, Serial No. 75,557

Term of patent 7 years

To all whom it may concern:

Be it known that I, Samuel A. Snell, a subject of the King of Great Britain and Northern Ireland, residing at Toledo, in the county of Lucas and State of Ohio, have invented a new, original, and ornamental Design for a Velocipede Frame Member, of which the following is a specification, reference being had therein to the accompanying drawing forming a part thereof, wherein:

Figure 1 is a side elevation of a velocipede frame member embodying my new design;
Figure 2 is a front elevation thereof; and
Figure 3 is a top plan view thereof.

I claim:

The ornamental design for a velocipede frame member substantially as shown.

SAMUEL A. SNELL.
